CLAIM

The ornamental design for a wireless omnidirectional microphone, as shown and described.

DESCRIPTION

FIG. 1 is a front elevational view of a wireless omnidirectional microphone showing the new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a top, front, and right perspective view thereof; and,

FIG. 8 is a bottom, rear, and right side perspective view thereof.

The broken lines illustrate portions of the wireless omnidirectional microphone in which the design is embodied that form no part of the claimed design.
